Primary Examiner — Katherine A Holbrow*Assistant Examiner* — Riya Salil Kamat(74) *Attorney, Agent, or Firm* — Birchwood IP(57) **CLAIM**

The ornamental design for a slide, as shown and described.

DESCRIPTION

FIG. 1 is a perspective view of a slide, showing my new design;
 FIG. 2 is a top view thereof;
 FIG. 3 is a bottom view thereof;

FIG. 4 is a left side view thereof;
 FIG. 5 is a right side view thereof;
 FIG. 6 is a rear view thereof; and,
 FIG. 7 is a front view thereof.

The broken lines shown illustrate portions of the slide and form no part of the claimed design.

1 Claim, 7 Drawing Sheets(56)
